Patented May 25, 1965

201,184

CABINET FOR A GRAPHIC IMAGE PROCESSOR

Ronald I. Conway, Kingston, Clarence F. Graser, Poughkeepsie, and William S. Sheppley, Jr., of Rhinebeck, N.Y., assignors to International Business Machines Corporation, New York, N.Y., a corporation of New York

Filed Apr. 30, 1964, Ser. No. 79,758

Term of patent 14 years

(Cl. D26—5)

FIG. 1

Des. 201,184

PAGE 2

FIG. 2

FIG. 3

FIG. 1 is a perspective view showing the cabinet incorporating our new design as seen from the left front side.

FIG. 2 is a perspective view of the rear of FIG. 1.

FIG. 3 is a plan view of our design.

We claim:

The ornamental design of a cabinet for a graphic image processor, substantially as shown.
